UNITED STATES PATENT OFFICE

108,102

DESIGN FOR A VACUUM CLEANER CASING

Harley J. McAllister, Chicago, Ill.

Application June 11, 1937, Serial No. 69,802

Term of patent 3½ years

To all whom it may concern:

Be it known that I, Harley J. McAllister, a citizen of the United States, residing at Chicago, in the county of Cook and State of Illinois, have invented a new, original, and ornamental Design for a Vacuum Cleaner Casing, of which the following is a specification, reference being had to the accompanying drawing, forming part thereof.

Fig. 1 is a view in side elevation of a vacuum cleaner casing showing my new design, the opposite side of the same presenting substantially the same appearance as the side herein shown except

that no drawer front is found on the opposite side.

Fig. 2 is a plan view of the vacuum cleaner casing;

Fig. 3 is an end view looking at the left end of Fig. 1; and

Fig. 4 is an end view of the vacuum cleaner casing looking at the right end of Fig. 1.

I claim:

The ornamental design for a vacuum cleaner casing as shown and described.

HARLEY J. McALLISTER.
